UNITED STATES PATENT OFFICE.

KATHLEEN A. DUFF, OF SAN FRANCISCO, CALIFORNIA.

ATTACHMENT FOR STOVES.

SPECIFICATION forming part of Letters Patent No. 772,558, dated October 18, 1904.

Application filed December 31, 1903. Serial No. 187,846. (No model.)

To all whom it may concern:

Be it known that I, KATHLEEN A. DUFF, a citizen of the United States, residing at San Francisco, in the county of San Francisco and State of California, have invented a new and useful Attachment for Stoves, of which the following is a specification.

This invention is an attachment for stoves, and although particularly adapted for use in connection with oil heating-stoves it can be used in connection with coal and wood stoves.

The object of my invention is to provide a rack surrounding the cylindrical portion or body of the stove upon which light articles can be hung for the purpose of drying them.

With this object in view the invention consists in the employment of a ring which is adapted to surround the stove, said ring being held in a horizontal position by means of brace-rods connected to the stove.

The invention consists also in certain details of construction hereinafter fully described, and pointed out in the claim.

In the drawings forming part of this specification, Figure 1 is a perspective view of a stove provided with my attachment. Fig. 2 is a sectional elevation. Fig. 3 is a plan view of the ring.

Referring to the drawings, A indicates a stove which may be of any desired construction so long as it embodies a cylindrical sheet-iron shell or body portion, and surrounding this cylindrical body portion is the metallic ring B, formed of wire and galvanized or nickelized to prevent rust. This ring is formed with indentations B' at regular intervals, and connected to the said ring at the points of in-

dentation are the brace-rods C, said rods being coiled around the ring at the indentation, as shown at C' in Figs. 1 and 2. The upper 40 ends of said rods are hooked or bent, as shown at C'', and pass through perforations A', produced in the body of the stove adjacent the upper end. The lower ends of the rods are bent back upon themselves, as shown at C''', 45 and then given a second bend, as shown at C'', providing a hook which is adapted to be passed through the aperture A'', produced also in the body of the stove, the return-bend C''' resting upon the outer side of the stove, as 50 most clearly shown in Figs. 1 and 2. By means of these brace-rods C the ring B is held in a horizontal position at a sufficient distance from the stove, and when it is desired to dry small articles—such as handkerchiefs, towels, 55 and the like—they can be hung upon the ring.

It will thus be seen that I provide an exceedingly cheap and simple attachment capable of carrying out all the objects hereinbefore mentioned.

Having thus fully described my invention, what I claim as new, and desire to secure by Letters Patent, is—

A stove attachment comprising a ring having indentations at regular intervals, the brace-rods connected to the ring at the indentations, the upper ends of the brace-rods being hooked, the lower ends being formed with a return-bend and a hook, substantially for the purpose set forth.

KATHLEEN A. DUFF.
